MACHINE FOR MAKING CUSHIONED PADS

Russell A. Wetherell, Attleboro, Mass., assignor to
 The Mason Box Company, Attleboro Falls,
 Mass., a corporation of Massachusetts

Application September 30, 1948, Serial No. 52,110

4 Claims. (Cl. 154—41)

1

This invention relates to an improved machine for applying a flexible covering material of an ornamental or decorative character to a relatively stiff backboard and more especially to a backboard having on one surface a cushioned material to form a cushioned pad for use in jewelry boxes and the like. The principal object of the invention is to provide a machine which will effect wrapping of the pads without wrinkling, at the corners rapidly, efficiently and with a minimum of skill required on the part of the operator according to the method illustrated, in my pending application Serial No. 131,334 filed December 6, 1949 covering the article per se and its method of manufacture.

The machine illustrated herein for making the pads has a support for holding the backboard, cushion material and covering material in superimposed relation with the marginal portions of the covering material bent into engagement with the peripheral edge face of the blackboard and wipers arranged to operate substantially in the plane of the uncushioned surface of the backboard to bend the covering material into engagement with the uncushioned surface of the backboard. The wipers include corner and side wiping members. The former are actuated to first wipe in the material at the corners of the backboard followed by the latter which wipe in the intermediate material. Movement of the wipers is effected by power operated means and delayed action linkage is interposed between the power operated means and the side wipers to delay their movement so that the corner wipers will perform their operations first. The support includes a forming member and a carriage, each of which has a cavity therein for reception of the superimposed backboard, cushion and covering material and are movable relative to each other to receive the backboard, cushion and covering material at a loading position, move them to a position beneath the forming member, force them into the cavity in the forming member and hold them there until the wipers engage the under surface of the backboard. The carriage is movable from a loading position at the front part of the machine to a presenting position in timed relation with the wiping action so that while the wipers are fulfilling their operation, the carriage is moved back into loading position to receive the component parts of the pad and is in readiness for the next operation. To apply pressure while the wipers are in closed position and to facilitate removal of the finished pad, a combination pressure plate and ejector is

2

associated with the forming member which bears upon the cushioned surface of the pad. After the wipers are closed pressure is exerted, and just before the wipers open, pressure is released.

- 5 This insures good contact of the adhesive on the backboard with the covering material. In addition, when the wipers have retracted, this combination pressure plate and ejector forces the pad from the cavity onto a tray which is arranged to be swung from a position beneath the forming member to an accessible position at the front of the machine. To insure the formation of smooth, unwrinkled corners, the cavity in the forming member has at its corners recesses into 10 which the fullness of the covering material caused by constriction thereof where it bends around the same may expand.

The invention will now be described in more detail with reference to the accompanying drawings in which:

- 20 Fig. 1 is a vertical front elevation of the machine showing the carriage in loading position;
 Fig. 2 is a vertical side elevation of the machine as seen from the left side of Fig. 1;
 25 Fig. 3 is a vertical section through the forming device and carriage showing the backboard, cushion and covering material forced into the forming opening in the folding member and held therein ready for wiping;

30 Fig. 3^a is a plan view of the folding member inverted, with the covering material forced into the opening therein and with the fullness of the corners occupying the cavities at the corners of the forming opening;

35 Fig. 4 is a plan view to somewhat smaller scale showing the wiping means as seen from its under side and in retracted position;

Fig. 5 is a vertical section on the line 5—5 of Fig. 2;

40 Fig. 6 is a vertical section through a fragmentary portion of the carriage;

Fig. 7 is a plan view to larger scale of the wiping means as seen from its under side with the wipers partially advanced so that the corner wipers engage the corner portions of the covering material;

Fig. 8 is a vertical section on the line 8—8 of Fig. 7;

Fig. 9 is a section on the line 9—9 of Fig. 7 showing the shape of the wiper blades;

Fig. 10 shows a fragmentary portion of a pad in a process of being covered and the formation of the fold at the corner thereof; and

Fig. 11 shows a bottom view of a completed pad.

Referring to the drawings, the machine 10 comprises essentially a forming device 12, a carriage 14, and wiping means 16, the aforesaid appliances being assembled together in operating relation upon a frame 18.

The frame 18 is comprised of a pair of spaced channel-shaped castings 20 rigidly joined at their top ends by a pair of spaced bars 22 welded to the opposite sides thereof and a brace 24 fastened between them at their lower ends to form a rigid framework within which the operating parts may be mounted. Other shelves and supports for carrying the operating parts of the machine are fixed to and within the frame as will appear hereinafter.

The carriage 14, shown most clearly in Figs. 1, 2 and 5, is arranged to move in a horizontal plane from the front of the machine inwardly to a loading position beneath the forming device 12 on a pair of spaced horizontally disposed rails 26 which are set on edge and fixed at their opposite ends to the bars 22 so that inverted V-shaped slide ways are provided. The carriage 14 includes a flat, substantially rectangular plate 28 (Fig. 5) to the four corners of which are fastened blocks 30 which have in their under surfaces V-shaped grooves 32 for engagement with the inverted V-shaped slide ways of the rails 26, thereby providing for sliding movement of the carriage along the rails and at the same time preventing lateral displacement. To the upper surface of the plate 28 there is fastened a platform 34 which is held spaced therefrom by a pair of spaced bars 36. The platform 34 has a shallow recess 38 in its top surface to receive and hold an adapter plate 40 having formed centrally thereof an opening 42 which extends through the plate from top to bottom and a concentrically arranged, somewhat shallow, larger recess 44 in its upper surface. The opening 42 is of a size and configuration to receive a back-board *b* and a cushion member *c* which form the component parts of the cushioned pad. The covering material *C* which is to be applied to the backboard and cushion member, as will appear hereinafter, is disposed above the cushion material *c* in the shallow recess 44 with its marginal edges *m* extending beyond the edges of the cushion material and backboard (Fig. 6). The shallow recess 38 in the platform 34 is open at one end to permit the adapter plate 40 to be slid off of the platform and replaced by an adapter plate having an opening of different size so that the apparatus may be used to cover different size cushioned pads. An opening 46 is formed centrally of the platform 34 so that it communicates with the opening 42 in the adapter plate 40, and in this opening there is situated a flat head 48 formed at the upper end of a post 50, the latter extending vertically downward through an opening 52 formed in the plate 28 and through a sleeve 54 fixed to the under side thereof, a keyway and key being provided for preventing rotation of the post in the sleeve. The post 50 is held at its lowermost position by gravity. Three small springs 60 are provided on the plate 28 which act as a cushion for the flat head 48 these springs being equally spaced about the post and set into recesses 61 formed in the plate and head. This spring cushion also limits the downward movement of the post by engagement with the plate 28. As thus held, the upper surface of the flat head 48 is flush with the upper surface of the platform 34. By moving the post 50 vertically, the backboard, cushion 75 this plate. By movement of the rod 92 in a

and covering material may be forced out of the adapter plate 40 and into the forming device 12 which will now be described, this being accomplished as will appear hereinafter at a time when the carriage is situated directly beneath the forming device. To insure that the carriage 14 does not bound back slightly after reaching its full forward position, which would result in the adapter plate 40 not remaining directly in line vertically with the forming device 12, a means is provided to prevent this in the form of a ledge 66 (Fig. 1) fixed to the under side of the plate 28 with which there is engaged a roll 64 fixed to the upper end of a rod 62, the latter projecting down through a hole in a bar 23 and having on it a spring 68 engaged between the under side of the bar 23 and the head of the rod. This holds the carriage firmly against the rails 26 and prevents the carriage from moving until driven mechanically.

The forming device 12 which is most clearly shown in Fig. 5 is supported above the carriage 14 by four vertically disposed posts 72 fixed at their lower ends to the upper ends of the castings 20 and by horizontally disposed bars 74 fastened to the top ends of the posts, and extending transversely of the machine which are reinforced by spaced bars 76 extending from front to back and welded to the bars 74. To the under side of the bars 76 there is welded a rectangular plate 78. There are attached to the central portion of the under side of the plate 78 a spacer member 80 made of asbestos or other suitable material to minimize heat transmission to the top of the machine where heat is neither needed nor desirable, and a forming block 82, suitable means being provided for attaching these elements to the plate. The forming block has in it a number of passages 81 (Fig. 3) running through it from one edge to an opposite edge within which may be disposed heating elements *E*. The forming block also has in its lower surface and extending from front to back thereof a channel 84 having undercut lateral edges within which there is slidably disposed a folding member 86 having a substantially rectangular opening 88 formed through it in the central portion thereof which is of such size and configuration as to receive the covering member *C*, cushion member *c* and back-board *b* in the order named. The folding member 86 has in its exposed surface at each corner of the opening 88 an inclined cavity or recess 90 which originates in the vertical walls thereof and extends upwardly and outwardly through the top surface of the member. The cavity 90 is adapted to receive the excess covering material which is produced at each corner by bending the marginal edges of the covering material consistently at each corner into a point, or peak of such shape that the action of the thin edge of a wiper blade will consistently draw this excess corner material toward the center of the back-board and away from its edges, thus forming the triangular fold of covering material shown in Fig. 11. It is evident that if the size of the pad is to be changed, the folding member 86 may be withdrawn and replaced with one having a larger or smaller opening therein. Vertical openings are formed through the forming block 82, the spacer 80 and the plate 78 through which passes a rod 92 to the lower end of which is fixed a flat plate 94 situated with the opening 88 against the block 82 so that the covering material when forced into the opening rests against

direction to force the plate 94 downwardly, pressure may be applied to cause firm contact of the adhesive on the backboard with the covering material and also the covered backboard may be forced out of the forming device.

The foregoing appliances serve to hold the component parts of the pad in a position to be operated upon by the wipers 16. To accomplish this, that is positioning of the component parts for wiping, a backboard b is placed within the opening 42 (Fig. 6) of the carriage, cushion material c is placed upon the backboard, and then covering material C is placed upon the cushion in the recess 44. The loading device is then moved inwardly along the rails 26 to a position directly below the forming device 12, whereupon the post 50 is raised so as to eject the backboard, cushion and covering material from the carriage and force the covering material, cushion and backboard in the order named into the opening 88 of the forming device against the plate 94, the marginal edge of the covering material thereby being folded down into engagement with the edge faces of the cushion and backboard and projecting downward beyond the exposed under surface of the backboard, as shown in Figs. 3 and 3^a. As thus folded there is an excess of covering material at the corners which produces puckers P. This puckering or fullness at the corners is, however, taken up by expansion of the covering material into the inclined cavities 90 at the corners of the folding member 86 which causes the covering material consistently to form peaks pointed directly toward the corner wiper blades. In accordance with this invention, while the covering material is held in this position, that is, with the marginal edges substantially at right angles to the bottom of the backboard and the corner portions thereof expanded into the cavities 90, the covering material is wiped inwardly over the exposed bottom surface of the backboard by first wiping the corner portions thereof inwardly and then wiping the intermediate portions inwardly beneath the in-wiped corner portions. This is accomplished, as will now be described, by the wiping means 16. The in-wiped marginal edges are held in place by an adhesive as will appear hereinafter.

The wiping means 16 (Figs. 2 and 5) is fastened to the under side of the plate 78 to operate in a plane which is substantially coincident with the bottom surface of the forming block 82. To this end a pair of spaced bars 100 are fastened to the under side of the plate 78 and from these bars project downwardly four short posts 102 to the lower ends of which are pivotally fastened by means of shoulder bolts 106 arms 104, two of these being arranged at each side of the machine and between the outer ends of corresponding arms 104 at the front and rear of the machine are pivotally fastened bars 108, the connection between the arms 104 and bars 108 being made by way of slots 110 and shoulder bolts 112 so that there is a limited amount of free movement between the connected ends. The inner ends of the arms 104 at each side are pivotally connected at 114 to a pair of short links 116 which in turn are pivotally connected at 118 to a rod 120. Movement of the right-hand rod 120 in a direction to the right, as shown in Fig. 7, swings the front and rear links 116 apart thereby pivoting the arms 104 in clockwise and counterclockwise directions respectively about their pivot points 106 so as to move their inner ends inwardly, and at the same time to

draw the bars 108 toward each other. Movement of the left-hand rod 120 toward the left produces a corresponding movement of the opposite ends of the bars 108 toward each other. Movement of the rods 120 in opposite directions reverses the movement of the arms 104 thereby separating their opposite ends and moves the bars 108 away from each other. A spring 122 is fastened to the outer ends of each pair of arms 104 at each side of the machine to eliminate sloppiness in the movement of the linkage. The wipers are operated by the aforesaid linkage as will now appear. To the bottom surface of the forming block 82 and the folding member 86 there are fastened a plurality of guide members 124, 126 and 128 for accommodation of the wiping members, each of these guide members having undercut channels 130 therein (Fig. 7). The guide members 124 accommodate T-shaped corner wipers which comprise a shank portion 132 arranged to slide in the channel formed in the guide and a blade portion 134. The guide 124 is so arranged that it makes an angle of substantially 45 degrees with the edges of the opening 88 in the folding member 86 hence as the blade 134 is moved inwardly, its leading edge which engages the covering material at the corner will be moving in a direction substantially normal to a line bisecting the corner. The rear end of the shank 132 of each corner wiper is connected for operation to one of the arms 104 by a short connecting link 138. To prevent play in the movement of the wiper, a gib 140 (Fig. 8) is placed within the groove 130 of the guide 124 against one edge of the shank 132 and is held yieldably pressed thereagainst by spaced springs 142 entering recesses 144 in the side of the guide and bearing at one end against the gib and at their opposite ends against an abutment 146 screwed to the block 82. The side wipers are also T-shaped and comprise a shank 148 and a blade 150, the former being slidably received in the guides 128 and being connected by pins 152 and slots 154 to substantially triangular plates 156. The triangular plates 156 are fastened by screws 158 to the bars 108. The end wipers comprise a shank portion 160 and a blade 162, the former being slidably received in the guides 126 and having their outer ends connected by pivoted links 164 to levers 166 (Fig. 5). Each lever 166 has at its free end a follower 168 which rests in a slot 170 formed in the upper face of a block 172, the latter being fastened to the inner end of the rod 120. By reason of the aforesaid construction, movement of the rods 120 in either direction will impart immediate motion to the corner wipers to move them inwardly or outwardly but the motion of the side wipers and the end wipers will be delayed by the length of the slots 154 in the side wiper connections and the slots 170 in the end wiper connections. The ratios of the linkages for moving the wipers into and out of operative position are proportioned so that the corner wipers 134 first engage the covering material at the corners of the forming device and begin to wipe the material in over the bottom surface of the backboard prior to the engagement of the side and end wipers with the covering material. In their inoperative position (Fig. 4) the blade portions of the end wipers and side wipers 162 and 150 lie within the blade portion of the corner wipers 134. The delay action referred to above however delays the movement of the end and side wipers 162 and 150 until the blade portions of the

corner wipers 134 have engaged the corners. At this time, as shown in Fig. 7, the blade portions of the end wipers 162 are behind the blade portions of the corner wipers, the latter having been moved by them. Since the blades of the end and corner wipers overlap at this point, recesses 134' are made in the end portion of the blades of the corner wipers on their upper sides next to the end wipers and corresponding recesses are made in the end portion of the end wipers on their under sides so that one may move by the other without interference. The side wipers 150, however, do not interfere with the movement of the corner wipers since they lie ahead of the corner wipers when the latter are in engagement with the corners. The positions of the various wipers when they have completed their in-wiping movement is shown in dotted lines in Fig. 7. The wiping actions of the wiper blades in the manner prescribed starts a fold F at each corner of the excess covering material and as it is laid down (Fig. 10) by the corner wipers, the side and end wipers come in and wipe the marginal edges along the sides and ends beneath the corner folds so that while the folding at the corners starts first, the sides and ends are folded in before the corner folds are completed and lie beneath the same.

The wipers, as shown in Fig. 9, have broad, thin, fin-like edges 176 and subjacent flat wiping surfaces 178, all of which lie in a common plane.

It is customary to secure the wiped-in edge of the covering material to the bottom surface of the backboard with adhesive, and this is accomplished herein by previously applying adhesive to either the marginal edge of the upper material or the bottom surface of the backboard, or both, the adhesive being of a heat-sensitive type. The heating elements E keep the forming block 32 hot enough so that as the marginal edges of the covering material are wiped in over the bottom surface of the backboard, the adhesive will be activated and secure the marginal edges of the covering material in place. In addition to heat, some pressure is required. This is furnished by the combination pressure plate and ejector. When the wipers are at their "in" position a downward motion of rod 92 presses the covering material and backboard against the wipers. Prior to the wiper's movement toward their "out" position, rod 92 moves upward releasing the pressure.

After the wiping action has been completed, the finished pad is ejected from the forming block 32 by downward movement of the rod 92 and the plate 94 which forces the pad from the folding member 86 and allows it to drop onto a tray 180 (Fig. 1) fixed to an arm 182 which is carried by a sleeve 183 mounted to turn freely on one of the posts 72, the tray being automatically swung into a position to receive a finished pad and then deliver it to the front of the machine as will appear hereinafter.

The aforesaid appliances are operated in a manner to produce the desired results by power-operated mechanism situated in the lower part of the frame. As illustrated, an electric motor M situated near the front of the machine provides the motive force and is bolted to a bracket 184 fastened to the brace 24. From the motor M a horizontal shaft 186 extends through the right side casting and to the shaft there is secured a V-pulley 188 over which there passes a V-belt 190 to a second V-pulley 192, the latter being secured to a horizontal shaft 194 (Fig. 2) spaced

75 rearwardly of the motor shaft. The horizontal shaft 194 is supported in spaced bearings 196 fastened to the top side of a shelf 198, the latter being secured to the back of the frame. The shaft 194 is connected by way of a conventional clutch (not shown) to a shaft 206 journaled in bearings 210 and has thereon a worm 208. The clutch may be engaged and disengaged by a conventional shifting fork 200 pivoted at 202 to a bracket 204 fixed to the rear of the frame and operated by a shift bar 201 which extends forwardly to the front of the frame and has a handle 203 fastened thereto so as to be operated from the front of the machine. Optionally, of course, a foot pedal could be used in place of a handle. The worm 208 meshes with a worm gear 212 which is fastened to a horizontal cam shaft 213 extending from front to back and journaled in spaced bearings 214, two of which are supported on a shelf 218 and one of which is supported at the upper end of a post 216. The shelf 218 is situated above the shelf 198 and rests on a pair of angles 220 fixed to the inside of the frame. The post 216 is fastened to the upper side of the bracket 198 at the rear of the frame. On the cam shaft 213 at the back of the frame there is fixed a gear 224 which meshes with a gear 226, the latter being fixed to a short horizontal shaft 228 extending at right angles to the cam shaft 213, and on this short shaft there is freely mounted a block 230 which is adapted to slidably occupy a slot 232 formed in an arm 234. At each end of the slot 232 and at opposite sides of the arm are fixed cam followers 236 with which cooperate cam arms 235 which are fixed at one end to the shaft 228. These cams are so arranged that during rotation of the shaft 228 one of the cam arms 235 will operate upon one cam follower 236 to move the arm 234 linearly in one direction and the other will move the arm linearly in the opposite direction, thereby producing reciprocation of the arm. The lower inner end of the arm 234 is pivotally connected at 238 to a rocker 240, the latter being pivoted to the frame at 242 and connected at its opposite end by a link 243 to the under side of the carriage 14. Reciprocation of the arm 234, therefore, will rock the rocker 240 and hence move the carriage 14 along the rails 26 from loading position to operative position and vice versa. As soon as the carriage has been moved to a position directly below the forming device, the covering material, cushion and backboard are ejected from the carriage and forced into the forming device by vertical movement of the post 50, and this is effected when the loading device is in this position by a cam 244 fixed to the shaft 213 within the frame which has a cam track 246 thereon. A cam roll 248 fixed in one arm of a bell crank lever 250 pivotally supported in the frame at 252 bears against the cam track 246 and rotation of the latter operates to tilt the bell crank lever about its pivot point and to move its other arm substantially vertically. The terminal end 254 of this arm is arranged to engage the lower end of the post 50.

Operation of the wipers is effected by a pair of cams 256 and 258 fastened to the cam shaft 213 within the frame which have in their opposite surfaces cam grooves 260 and 262 respectively, within which operate cam followers 264 (Fig. 1) fixed to the ends of slide rods 266, each of which is slidably mounted in spaced brackets 268 fastened to the top of the shelf 218. The outer ends of the slide rods are pivotally connected to vertically disposed rocker arms 270 pivoted to the

sides of the frame at 212, and their upper ends are pivotally connected at 214 to the rods 120. Rotation of the cam shaft 213 will, therefore, by way of the cams 253 and 258 impart reciprocation to the rods 120 to move the wipers inwardly or outwardly.

During the time when the wipers are at "in" position, pressure must be applied and following the completion of the wiping operation, the completed pad must be ejected from the forming device. Both of these operations are accomplished by downward movement of the rod 92. Movement of the rod 92 is effected by a cam 276 (Fig. 2) mounted on the cam shaft 213, just inside the frame, upon which rides a cam follower 278 pivotally mounted at the lower end of a cam rod 280. The rod rises vertically through a sleeve 282 fastened to the frame and has connected to its upper end at 284 a lever 286, the latter being pivoted at 288 to a post 289 fixed to one of the bars 76. A tension spring 290 connected to the rod 280 and to the frame normally holds the lever 286 in a retracted position. Upward movement of the rod 280 produced by a high spot in the cam surface 276 will tilt the forward end of the lever 286 down and, by way of a ball 292 situated at the upper end of the rod 92, will bring about depression of this rod. The rod is guided in its movement by a bracket 294 and is returned to inoperative position by the spring 290.

The tray 180 for receiving the ejected pad is normally held beneath the forming device 12 by a spring 181 attached to the free end of an arm 185 which is fixed to the sleeve 183. To effect movement of the tray, a rod 187 (Fig. 2) having a bifurcated forward end 189 is pivotally attached to the arm 185. The rear end of the rod is also bifurcated and is connected to one arm of a bell crank lever 191, the other arm of which has a horizontal projection thereon to which is fastened a cam roll for engagement with the cam surface 193. The cam surface 193 is shaped so that the bell crank lever will oscillate the rod 187 in timed relation with the carriage so that as soon as the latter moves to loading position the tray will move to a position to receive the ejected pad, and as the carriage moves into ejecting position the tray will swing out to the front of the machine to discharge the pad.

In the operation of the aforesaid machine, the carriage 14 is first brought to a position at the front of the machine, as shown in Fig. 2, the backboard b is placed in the opening 42, cushion material c is placed above the backboard, and a suitable covering material C is then placed above the cushion in the recess 44 as shown in Fig. 6. The handle 203 (Fig. 2) is then rotated to operate the clutch and hence to connect the main cam shaft 213 to the continuously rotating worm gear 212 so as to effect rotation of the cam shaft 213. Thereafter, because of the specific arrangement of the various cams which impart movement to the parts, the formation of the pad is effected first by movement of the carriage 14 inwardly to a position directly below the forming device 12; 65 then by movement of the post 50, and hence the head 48, which lifts the backboard, cushion and covering material from the loading device and forces them into the forming device; then by movement of the wiping member 16 inwardly to 70 fold the marginal portions of the covering material into engagement with the bottom side of the backboard; then by movement of rod 92 and plate 94 to provide pressure to insure good contact of

adhesive; then by withdrawal of the wiping members; and finally by movement of the rod 92 and plate 94 to eject the finished pad onto the tray 180 whereupon the tray is operated to bring the pad to the front of the machine. The moving parts are timed so that during the wiping movement of the wipers the carriage 14 is moving back to loading position to receive a new charge of material and the tray 180 is moving beneath the forming device so as to be ready to receive the finished pad when it is ejected from the forming device, and that during movement of the tray to an out-of-the-way position, the carriage which is now loaded will be moving inwardly into ejecting position. As long as the clutch is left engaged, the machine will continue automatically provided the operator loads the carriage each time that it arrives at the front of the machine. Discontinuance of the operation of the machine may be effected by declutching the clutch.

It should be understood that the present disclosure is for the purpose of illustration only and that this invention includes all modifications and equivalents which fall within the scope of the appended claims.

I claim:

1. In a machine for applying a covering piece to a polygonal backboard to make a covered pad, said piece being larger than the backboard by a margin extending around its periphery, the combination of a holder having a polygonal opening to receive said piece and cardboard in superposition with said margin projecting past the edges of the cardboard and beyond the edges of the opening, the corners of the opening being recessed beyond the outline of the polygon to receive the fullness of the said margin at the corners, side and corner wipers to fold the side and corner portions of the margin over the backboard, and means to actuate said wipers in sequence so that the corner folds overlap the same faces of all the side folds.

2. A machine according to claim 1 further characterized in that said means actuates the wipers so that it is the outside faces of the side folds which are overlapped by the corner folds.

3. A machine according to claim 1 further characterized in that said means causes the corner wipers to start the corner folds before the side wipers start the side folds.

4. A machine according to claim 3 further characterized in that said means completes the movement of the side wipers before completing movement of the corner wipers.

RUSSELL A. WETHERELL.
